UNITED STATES PATENT OFFICE

JAMES F. O'BRIEN, OF CHICAGO, ILLINOIS.

POWDER-MILL MACHINERY.

1,071,258.

Specification of Letters Patent. Patented Aug. 26, 1913.

Application filed June 3, 1912. Serial No. 701,256.

To all whom it may concern:

Be it known that I, JAMES F. O'BRIEN, a citizen of the United States, residing at Chicago, in the county of Cook, State of Illinois, have invented new and useful Improvements in Powder-Mill Machinery, of which the following is a specification.

This invention relates to the machinery of a plant particularly adapted for carrying out processes of manufacture for chlorate-carbohydrate explosives and the like; and this present invention consists particularly in machine constructions and arrangements for carrying out a process of manufacture which is entirely devoid of heat or friction and in which the explosive is at all times free and unconfined.

I have described in various co-pending applications the general composition and manufacture of my explosive. Therein I have explained how the different ingredients are prepared and then mixed together in a simple manner and then granulated and dried. This process of manufacture requires (1) a disintegrator for breaking up the chlorate into small particles, the chlorate being deliquescent and therefore apt to be in lumpy condition; (2) a mixer in which the various solid and liquid ingredients are brought together and thoroughly mixed until homogeneity is attained; (3) a granulator in which the mixed explosive is divided into granules of a uniform size; (4) a drier in which the excessive moisture is removed; and (5) an insulator in which the granules are supplied with a coating of powdered graphite or the like to give them a smooth exterior and good appearance. I have arranged all of these machines into one complete simple plan, the materials being passed by gravity from one machine directly to the next machine and passing through the whole plant without friction and without application of heat and without confinement. (The importance of non-confinement is seen when I state that, although it requires a flame under any circumstances to detonate my explosive, it is utterly impossible to detonate, even by flame, if unconfined.) This is the prime feature which I wish to emphasize throughout the following specification, and is the feature which is most novelly involved in the mixing and granulating machines. After describing the plant in general I wish to describe these two particular machines in detail, and to cover

in the following claims those features which are common to both machines and some features which are found only in one.

I have shown my preferred arrangement of mechanisms and my preferred construction of the individual machines in the accompanying drawings, in which:

Figure 1 is a vertical sectional elevation showing my complete plan. Fig. 2 is a detail longitudinal section of the mixer. Fig. 3 is an exterior elevation of the same. Fig. 4 is a section taken on line 4-4 of Fig. 3. Fig. 5 is a longitudinal section of the granulator. Fig. 6 is a section taken on line 6-6 of Fig. 5. Fig. 7 is an exterior elevation of the granulator. Fig. 8 is an exterior elevation of the drier. Fig. 9 is a vertical central section of the same.

In the drawings 10 may designate a suitable frame and housing within which I may place my complete plant, the plant being preferably located on a slope so that the machines may be conveniently arranged in succession above each other so that gravitational feed may be employed throughout. The uppermost of the machines is disintegrator 20. This disintegrator may be of any desired character, being designed merely to break up the pieces of potassium chlorate so that a finely divided material may be supplied to the mixer 21. Mixer 21 is arranged directly beneath a chute 22 leading from the disintegrator, and a chute 23 leading from the mixer discharges directly into the granulator 24. From granulator 24 a suitable non-metallic elevator 25 leads up to the hopper 26 of drier 27. The granulated explosive passes through this drier then out through a discharge chute 28 and passes to insulator 29. From the insulator it is ready to be suitably packed and loaded for shipment. Throughout this plant the explosive is at all times unconfined, the chutes being free and open and all the machines of ample capacity. There is no flame used in any portion of the plant; and the powder never passes where it can enter between two frictionally engaging parts.

In Figs. 2, 3 and 4 I have illustrated in detail the construction of the mixer. This mixer has a semi-cylindrical drum 30 with a peripheral wall 31 preferably of smooth brass. The drum 30 has hollow trunnions 32 which rest in suitable bearings 33 on frame 34. The drum has a cover 35 having a door 36 on either side. It is revoluble on

its bearings by means of gear teeth 37 which mesh with a pinion 38, the pinion being rotatable by hand crank 39. The drum may thus be turned in the direction indicated by the arrow in Fig. 3 so that its contents may be easily dumped into the chute 23 directly below.

Extending centrally through hollow trunnions 32 and freely spaced therefrom, is a rock shaft 40 having cranks 41 on its ends connected by a rod 42 to a revolving crank 43. Means are provided for adjusting the stroke of connecting rods 42 so that the oscillation of cranks 41 may vary. The crank 43 is mounted on a shaft 44 revolved through the medium of a belt connection 45. Shaft 40 has bearings 46 which securely hold it centrally spaced in the hollow trunnions 32 in such manner that it is impossible for it to come into contact with the inner surfaces of the trunnions. Shaft 40 carries the rocker arms 47 which support mixing wires 48 and scrapers and followers 49. Scrapers 49 are mounted on pivots 50 which are adjustable by placement in the different apertures shown, so that the angle of the scrapers to the inner periphery of the drum may be varied. These scrapers rest upon the inner periphery by their own weight only; and their members 51 which engage directly with the brass of the periphery are preferably of wood or similar material. The stroke of the rock shaft and arms is such that each scraper is carried down to the central vertical plane passing through shaft 40, riding over the material in the bottom of the barrel on the down stroke and scraping the material from the brass periphery on the up stroke. Thus the scrapers perform two distinct functions, scraping the material from the periphery and thus helping to thoroughly mix it, and passing over the material directly after the mixing wires 48 and thus obliterating the furrows made by those wires. The wires are placed in staggered relation, as illustrated in Fig. 4, so that they thoroughly divide and turn over the materials, moving them from side to side and causing them to come into such intimate contact with each other as to form a perfectly homogeneous mixture. The wires 48 never come into contact with the inner periphery of the drum, being rigidly held with their ends at a short distance therefrom.

In the operation of this machine a charge of the solid ingredients is placed in the drum through one or both of doors 36 and the rock shaft started in operation. The liquid ingredients are then fed through a flexible connection 60 into a suitable tank 61 carried by the rocker arms between the two sets of mixing wires. The lower end of this mixing tank is perforated, as at 62, so that the liquid ingredients are distributed

in a shower over the solid ingredients between the two sets of mixing wires. It will be seen that the supply of liquid ingredients is immediately followed by one or the other set of mixing wires and is immediately mixed into the solids by being thrown into intimate contact therewith. The result of this action, and of the action of scrapers 51 is to thoroughly and quickly mix the different ingredients together without the necessity of applying heat at any stage of the operation. It is seen that there can possibly be no friction between any metallic parts of the mixer, the only place having any friction whatever being on the scrapers 51. But these scrapers are made of such material that their friction cannot generate any great amount of heat or a spark. The drum is perfectly free and open; there is no confinement to make an explosion even if the charge in the mixer should be purposely ignited.

In Figs. 5, 6, and 7 I have illustrated in detail the construction of the granulator. This machine has a completely cylindrical drum 70 mounted on hollow trunnions 71 resting in suitable bearings 72. Bearings 72 are mounted on a suitable frame 73. The drum 70 is continuously revolved through the medium of a belt connection 74 with shaft 75 which is in turn rotated through gearing connections 76 from a shaft 77, the rotation of drum 70 being comparatively slow. The drum has two ends or heads 78 and a peripheral wall 79 of suitable wire screen. The materials are forced out of the granulator through this wire screen, being thereby limited in size; and they are fed into the granulator through openings 80 in one of the heads 78. Openings 80 connect each with a small sectional hopper or chute 81 which, taken all together, form a continuous ring of chutes on one end of the drum or barrel. The material is fed into these hoppers 81 from the chute 23, feeding always into the uppermost hopper 81, passing directly through its feed opening 80 into the interior of the drum. Thus, in spite of its continual revolution, the drum is constantly supplied with the mixed explosive ready for granulation.

Mounted in suitable bearings 90 there is provided a rock shaft 91 having a crank or arm 92 on its end connected by rod 93 to crank 94 on shaft 77. The revolution of shaft 77 (through the medium of belt connection 94) causes the rocking or oscillation of shaft 91 in the manner hereinbefore described in connection with the mixing machine. This shaft 91 carries two frames 95 and 96. Frame 96 carries two sets of raking rods or wires 97 somewhat similar to the mixing wires of the mixing machine. These raking wires oscillate back and forth through the layer of material which always

stands in the lower part of the drum, breaking the material up into small granules and working them through the screen of periphery 79. The periphery is constantly revolving; and a suitable stiff revolving brush 98 is carried by the frame 95, the bristles of the brush being arranged to poke through the screen periphery 79 and to thereby clean the periphery of any material tending to clog the openings. Thus, a great area of clean and clear screen is presented continuously beneath the raking wires 97, and there is no liability whatever of the screen becoming so clogged that the discharge of materials would cease. In fact, in practice we have found that the material is discharged very readily and continuously, the material passing through the machine very quickly. It is desirable to keep only sufficient material in the machine to cover the portions of the screen over which the rake wires 97 are oscillating.

It will be seen that the granulator has many points in common with the mixer. In the granulator there are no interior parts in direct contact except the peripheral screen and the revolving brush 98; but these parts are of such materials that they cannot create friction or cause a spark (in practice I prefer to make the brush of hog bristles). The raking wires 97 are spaced so that their ends never touch the peripheral screen; and it is impossible for the rock shaft 91 to come into contact with the trunnions 71. The parts are also arranged as regards end motion so that the shaft 91 cannot move longitudinally and cause the frame 95 and 96 to engage with the heads of the drum. I thus have what I term a perfectly frictionless machine, there being no parts in frictional contact where there is any exposure to the explosive. And, as I have stated in connection with the mixer, the granulator is perfectly open and free, thus rendering absolutely impossible a detonation of its charge.

I have also shown in the drawings, in Figs. 8 and 9, the construction of my drier. The material enters the drier and is distributed over a cone 100 and then passes downwardly alternately over inner truncated cones 100 and outer inverted truncated cones 102, passing in the general zig-zag direction indicated by the arrows in the upper part of Fig. 9. Heated or cold air passes upwardly from a chamber 103 at the lower part of the drier and then out through the openings between the inner cones 101 and into the regular space between the two sets of cones, passing finally to atmosphere between the outer cones 102. The air may be passed through the drier cold or may be warmed through the medium of a suitable steam coil 104. The explosive passes down between the cones, finally lodg-

ing in a sort of annular pocket designated by the numeral 105 from whence it gravitationally passes through openings in the lowermost outer cone 102, which openings are blocked by wooden blocks 106. The dry explosive passes then down into the discharge chute 28 which is arranged around the chamber 103. The disintegrator shown in Fig. 1 is merely a revolving screen arrangement inside a suitable casing, taking a charge of chlorate and working it through the screen. The insulator consists of a tumbling drum in which the powder and finely divided graphite are rolled over and over. I mention the construction of these parts to show that my process is safe throughout; that there is no friction, pressure, heat or confinement at any stage.

In the following claims I wish to secure particularly those features and combinations which are common to the mixing and granulating machines; being those features which result in a perfectly frictionless process of manufacture.

Having described my invention, I claim:

1. In powder machinery, a revoluble drum having a charging opening therein, hollow trunnions forming the supporting axis of the drum, bearings for said trunnions, an oscillating shaft extending through said drum and trunnions, the inner diameters of the trunnions being greater than that of the shaft, bearings for the shaft holding it approximately concentric with the barrel and trunnions and free from contact therewith, powder engaging members depending from the shaft close to the drum periphery, and means to oscillate the shaft to oscillate the powder engaging members over the lower part of the drum.

2. In powder machinery, a revoluble drum having axial openings at each end, a shaft extending through the drum and freely through said openings, bearings for the shaft in such position that the shaft does not contact with the drum at any point, spaced wires carried by the shaft and projecting radially therefrom to a point close to but not touching the drum inner periphery, a scraper carried by said shaft, and means to oscillate the shaft.

3. In powder machinery, a drum having axial openings at each end, a shaft extending through the drum and freely through said openings, bearings for the shaft in such position that the shaft does not contact with the drum at any point, spaced wires carried by the shaft and projecting radially therefrom to a point close to but not touching the drum inner periphery, a scraper carried by said shaft, a liquid distributor carried by the shaft, and means to oscillate said shaft.

4. In powder machinery, a frame, a drum with axial hollow trunnions journaled on the frame, a shaft passing through the trun-

nions and drum, the diameter of the shaft being much less than that of the interior of the trunnions, bearings for the shaft spaced outside the trunnion bearings in such position that the shaft is revolvably supported clear of the trunnions, both the shaft and drum being prevented from moving axially, radial arms carried by the shaft within but not touching the drum, radially extending members carried by the arms and extending close to but not touching the drum inner periphery, a liquid distributor on the arms, a scraper pivoted to the arms and adapted to rest upon and follow the drum inner periphery, and means to oscillate the shaft.

5. In powder machinery, a revolvable drum having a charging opening therein, hollow trunnions forming the supporting axis of the drum, bearings for said trun-

nions, an oscillating shaft extending through 2 said drum and trunnions, the inner diameters of the trunnions being greater than that of the shaft, bearings for the shaft holding it approximately concentric with the barrel and trunnions and free from contact therewith, a set of spaced powder engaging wires projecting radially from the shaft to points close to but not touching the drum periphery, and means to oscillate the shaft to oscillate the powder engaging members over the lower part of the drum.

In witness that I claim the foregoing I have hereunto subscribed my name this 24th day of May 1912.

JAMES F. O'BRIEN.
